DETUR TULLER

Attorneys:

UNITED STATES PATENT OFFICE.

FREDERICK NEUMANN, OF WEST MILWAUKEE, WISCONSIN.

SAW CLAMP.

Application filed April 9, 1926. Serial No. 100,861.

This invention relates to a combination saw-buck, saw-clamp, and table.

Objects of this invention are to provide a device which is collapsible and which may 5 be opened up to provide a saw-buck, saw-clamp or table, and yet, which is of simple and strong construction and not likely to get out of order.

Further objects are to provide a novel 10 form of device in which the table top is foldable, and is adapted to be used as a seat while the device is used as a saw-clamp, thus providing a device which is eminently suitable to this kind of work.

15 An embodiment of the invention is shown in the accompanying drawings, in which:

Fig. 1 is a view of the device opened up and used as a saw buck;

20 Fig. 2 is a view of the device as it appears when used as a saw clamp, such view showing in dotted lines the position of one of the parts when the device is used as a table; and

25 Fig. 3 is a vertical sectional view on the line 3—3 of Fig. 1.

Referring to the drawings, it will be seen that the device comprises a pair of inner legs 1 and a pair of outer legs 2 arranged in crossed relation. These pairs of legs are 30 joined by means of the braces 3 and 4 respectively. The inner legs 1 have secured thereto, by means of brackets 5, a transverse locking bar 8. This locking bar is rectangular, and is provided with triangular ends 9. 35 These triangular ends 9 are adapted to fit within notches 10 formed in the outer bars or legs 2 when the device is opened up as shown in Figs. 1 and 2.

It is to be noted further that the device is 40 provided with notches 11 in each of the legs. These notches are adapted to receive the folded table portion 12 as shown in Figure 2 when the device is used as a saw clamp. This folded table portion provides a seat 45 for the operator. Further, it will be noted that the transverse member 3 is provided with a locking bar or clamping bar 13 which is secured by means of a thumb nut 14 to one

end of such member. This clamping bar is adapted to hold a saw, such as indicated at 50 15, tightly against the member 3. A relatively large clamp 16 may be employed for the free end of the clamping arm 13 as shown most clearly in Fig. 3.

Thus, when the device is used as a saw 55 clamp, means are provided for rigidly holding a saw in position, and also for affording a seat for the operator.

It is also clear, as shown in dotted lines in Fig. 2, that the table portion 12 may be 60 opened up and placed across the upper ends of the bars or side members 1 and 2 to thus provide a table.

It will be seen that a simple type of device has been provided, and it will be seen further, that the device is strong and rigid.

Further, it is to be noted that the device may be folded into a compact shape when not in use.

Although the invention has been described 70 in considerable detail, such description is intended as illustrative rather than limiting as the invention may be variously embodied and as the scope of such invention is to be determined as claimed.

I claim:

In a device of the class described comprising two pairs of pivotally joined crossed legs, one element of each pair being joined to the other element of the other pair by a 80 transverse brace, a relatively heavy transverse brace joining the inner legs and projecting outwardly in line with the outer legs, said outer legs having notches adapted to receive the relatively heavy brace when the 85 legs are opened up, a saw clamp carried adjacent the end of one pair of legs, said legs having opposed notches on their inner side and a removable seat portion positioned between said notches.

In testimony that I claim the foregoing I have hereunto set my hand at Milwaukee, in the county of Milwaukee and State of Wisconsin.

FREDERICK NEUMANN.
